US0D1049910S

(12) **United States Design Patent** (10) **Patent No.:** **US D1,049,910 S**
(45) **Date of Patent:** **** Nov. 5, 2024**

(54) **SMART RING**

(71) Applicant: **Samsung Electronics Co., Ltd.**, Suwon-si (KR)

(72) Inventors: **Byungchan Lee**, Suwon-si (KR); **Jaehyung Hong**, Suwon-si (KR)

(73) Assignee: **SAMSUNG ELECTRONICS CO., LTD.**, Gyeonggi-Do (KR)

(**) Term: **15 Years**

(21) Appl. No.: **29/928,850**

(22) Filed: **Feb. 16, 2024**

(30) **Foreign Application Priority Data**

Aug. 18, 2023 (KR) 30-2023-0032186
Aug. 18, 2023 (KR) 30-2023-0032187

(51) **LOC (14) Cl.** **14-02**

(52) **U.S. Cl.**

USPC **D11/26**; D24/167

(58) **Field of Classification Search**

(57) **CLAIM**

The ornamental design for a smart ring, as shown and described.

DESCRIPTION

FIG. 1 is a front perspective view of a smart ring showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof.

The broken lines in the figures depict portions of a smart ring that form no part of the claimed design. The dot-dash broken lines in the figures represent a boundary of the claimed design and form no part of the claimed design.

1 Claim, 6 Drawing Sheets
